DISPLAY SIGN

Berl Treshansky and Meyer Treshansky,
Chicago, Ill.

Application July 14, 1932, Serial No. 622,382

12 Claims. (Cl. 40—132)

The present invention relates generally to display signs such as are used in store windows and like places for advertising purposes, and has particular reference to an improved display sign of this type which operates on optical principles to secure an intermittent automatic change of the images presented for view. The sign is of translucent material and the optical change is effected by projecting light rays through the sign for presenting one picture and then discontinuing the projection of the light rays through the sign for presenting another picture.

The primary object of the invention is to provide an improved display sign which is capable of presenting two totally distinct pictures or images in this manner. This involves completely obliterating one image or picture when the light rays are being projected through the sign, so that only the other image or picture appears. Heretofore, the majority of these display signs have been limited to the use of the same image outline for both pictures, the permissible variation being merely the superposition on this image outline of additional features of detail, color, etc. In view of the fact that the picture which is presented in our improved sign when no light rays are projected through the sign, is completely obliterated when the light rays are projected through the sign for displaying the second picture, we are enabled to present two totally distinct pictures, which might even bear no relation to each other whatever in either outline or composition, if such were desirable for the particular advertising use. By way of example, our improved sign is capable of alternately presenting to view a vacant lot and then a bungalow; an old dilapidated house and then an apartment building; a horse and buggy and then an automobile; an egg and then a chick, etc.

Another object of the invention is to provide an improved method of making a sign or composite picture having this characteristic. The general principle underlying such method is that when a photographic negative and a photographic positive of the same image are superposed on each other in exact registry the shadows of the one neutralize the high lights on the other, and vice versa, so that a uniform intensity of light will then be projected through the composite over every unit of area with no definition of the original image appearing. These light rays, projected through the second, totally distinct picture, take on none of the definition of the first image.

Other objects and advantages of our invention will appear from the following detail description

of a preferred embodiment of our improved display sign and of a preferred method of making the translucent sign portion thereof. In the accompanying drawing illustrating such preferred embodiment and method:

Figure 1 is a vertical cross sectional view through the physical structure of the sign including its supporting frame, reflecting back, etc., and also illustrating diagrammatically one preferred method of alternately illuminating the sign.

The other figures illustrate the method steps of producing the sign.

Figure 2 illustrates the original photographic negative of the image or picture which is to appear when no light rays are projected through the sign;

Figure 3 illustrates a positive reproduction of the original negative of Figure 2, such positive reproduction being made on translucent print paper or other suitable base material;

Figure 4 is a positive reproduction of the original negative of Figure 2, made on film, photographic plate or the like;

Figure 5 illustrates the original photographic negative of the second image or picture which is to appear when light rays are projected through the sign, and

Figure 6 is a composite reproduction of the positive of Figure 4 and the original negative of Figure 5, such composite reproduction being preferably on translucent print paper or other suitable base material.

Referring first to Figure 1, the translucent sign is generally indicated at 10, comprising a front sheet 11 and a rear sheet 12, on which the images or pictures are reproduced. To protect these sheets from moisture, atmospheric changes, the temperature of the light rays, etc., the front and back sides of the two sheets are covered by transparent panes of glass 14 and 15. This assembly of the sheets and glass panes is supported in a suitable frame structure 16, arranged in any desired manner for quickly and easily interchanging the sheets 11, 12. Extending rearwardly from the frame 16 is any suitable form of reflector 18 within which one or more lights 19 are mounted.

The sign operates entirely successfully when ordinary daylight, or any diminished value thereof available in a store window, is utilized to illuminate the front side of the sign for presenting one picture, and the light rays from one or more lights 19 are projected through the sign for presenting the other picture. In such uses, it may be desirable to shroud or hood the front

of the sign by a hood 21 extending from the top and sides of the sign, so as to give greater contrast or preponderance to the light rays projected through the sign from the light 19. We also 5
 5 template an embodiment wherein greater contrast or preponderance between the alternating light values can be obtained by placing a front light 24 in position to project its rays against the front of the sign, and by operating the lights 10
 10 19 and 24 alternately. In such latter embodiment, the front light 24 may be supported in the hood 21, with a suitable reflector 25 so positioned as to project the majority of the light rays therefrom down upon the front side of the sign. The 15
 15 back and front lights 19 and 24 can be illuminated alternately by any desired flasher switch, motor driven switch or the like. In Figure 1 we have illustrated a thermally operated flasher switch 27 which may be employed for this purpose. 20
 20 The latter comprises a suitable thermostatic element, such as a bimetallic strip 28 over which is wound a heating coil 29. A movable switch element comprising two contacts 31 and 32 is actuated by this thermostatic element. The two 25
 25 contacts 31 and 32 are mounted in insulated relation, as diagrammatically represented by the insulating blocks 33. The contact 31 is adapted to engage with a contact 34 connecting through wire 35 leading to the rear light 19, and the other movable contact 32 is adapted to engage with contact 36 connecting through wire 37 leading to the front light 24. Any suitable snap actuating mechanism, such as is diagrammatically indicated at 38, may be employed for transmitting 30
 30 motion from the thermostatic strip 28 to the movable contact elements 31, 32 for snapping the latter from one circuit closing position to the other. The supply circuit is indicated at 43, 44, the wire 43 being connected to one end of 40
 40 the heating coil 29, and the wire 44 being connected to the other terminals of both lights 19 and 24. The opposite end of the heating coil 29 is electrically connected with the movable switch contact 31. A shunt 45 bridges the heating coil 29, extending from the wire 43 to the other movable switch contact 32. When the switch is in the position causing contacts 31 and 34 to engage, the rear light 19 is illuminated and the current therefor is traversing the coil 29. When 45
 45 the thermostatic strip 28 reaches a sufficient temperature it flexes in a direction to throw the switch to the opposite position, thereby separating the contacts 31 and 34 and engaging the contacts 32 and 36. This cuts off the rear light 19 and illuminates the front light 24, the current for the latter passing through the shunt 45. When the thermostatic strip 28 has cooled to a sufficient degree it flexes in the opposite direction and thereby throws the movable switch contacts back to their preceding positions. 50
 50

Referring now to the preferred method of producing our changeable sign 11, 12, we shall assume that the picture to be displayed by exterior light or by the rays from the front light 24 is that of an old, dilapidated house and that the picture to be presented by the rays projected through the sign from the rear light 19 is that of a modern, attractive apartment building, which type of sign might conceivably be used for advertising purposes in a real estate office and which, for the purposes of the present disclosure, illustrates two widely contrasting images having no lines of definition in common. 55

The first step is illustrated in Figure 2, consisting in the making of a photographic repro-

duction of the house. The photograph may be taken of an actual house, or it may be taken of a drawing, painting or other pictorial representation of a house. The result is an original negative 51, preferably film, in which the high light values of the original image of course appear dark in the negative and the shadows appear light. For facility of describing and claiming the steps of the method, we shall designate this image of the house as image "A". 10

Following the preferred steps of the method, two positives are now made of this negative 51; one a positive reproduction on translucent print paper, designated 11 in Figure 3, and the other a positive reproduction on film, designated 52 in 15 Figure 4. In each of these the image "A" will appear in its natural light values, the high lights of the actual image appearing as high lights in both of these positive reproductions and the shadows appearing as shadows. The sheet 11 20 of Figure 3 is the front sheet 11 of the composite sign referred to in connection with Figure 1.

A photographic reproduction is now made of the second image which is to be presented when light rays are projected through the sign. This 25 photographic reproduction is represented by an original negative designated 53 in Figure 5. As previously remarked, this second image is that of an apartment building, and this image we shall refer to as image "B". Here again, this photo- 30 graphic reproduction may be made from an actual building, or from a drawing, painting or other artistic representation of such building. Of course, the high lights of the original image also appear dark in such negative and the shad- 35 ows light.

Figure 6 illustrates the next step—that of making a composite print prepared from the two films 52 and 53. This print, which is the sheet 12 of Figure 1, is preferably on translucent print 40 paper, and is preferably a contact print, made with the two films 52 and 53 one on top of the other in contact and held against the print paper. The reproduction on the paper 12 is a composition of images "A" and "B". On this 45 sheet 12 the light values of image "A" are reversed from the way they appear on sheet 11, i. e., the high light areas on sheet 11 appear as low light areas on sheet 12 and the low light areas of sheet 11 appear as high light areas on sheet 50 12. Referring now to image "B", as also reproduced in this composite print 12, this image "B" has its true light values since it is a positive of negative 53, i. e., the high light areas of the building and other portions of image "B" appear 55 as corresponding high light areas in the composite print 12, and the same is true of the low light areas. The sheet 12 is thus a composite reproduction showing image "A" in its negative light values and showing image "B" in its positive light values. 60

The sheets 11 and 12 are now brought into registry. This registry is obtained when the positive reproduction of image "A" appearing on sheet 11 is in register with the negative reproduction of image "A" appearing on sheet 12. Such registration might be effected mechanically by properly sized or perforated sheets, but a very simple and effective practice is to project light through the two sheets and move one 70 relatively to the other until image "A" completely disappears, whereupon registry between the positive counterpart of the image with the negative counterpart is assured. The registered relation between the two sheets 11 and 12 is then 75

permanently fixed, preferably by adhesively uniting the two sheets with a transparent adhesive applied over their entire contacting areas; although the sheets may only be cemented together at their edges or might be mechanically clamped together.

In displaying the sign as described above in connection with Figure 1, image "A"—the house—will stand out as a prominent clear-cut picture as long as the external light rays, either daylight or from the front light 24, predominate. At this time the light rays depicting the image or picture are solely rays reflected from the outer surface of the positive print 11, and all details of the image in their true light values are represented in this positive print. When the rear light 19 is illuminated, or the rear source of light preponderates over the front source, the negative reproduction of image "A" appearing on sheet 12 becomes the optical or reverse counterpart of the positive reproduction of image "A" appearing on sheet 11 and hence these negative and positive counterparts completely neutralize each other in so far as giving definition and graduated light values is concerned. Therefore, upon the illumination of the rear light 19, the image "A" is completely obliterated. These same light rays, however, in passing through the rear sheet 12, take on the definition and graduated light values of image "B" which are reproduced in this rear sheet. Since the reproduction of image "B" is positive in composite print 12, the resulting presentation of image "B" is in its true relation of light and dark areas.

The sheets 11 and 12 are preferably highly translucent for transmitting fairly high light intensity, and the negative and positive counterparts of image "A" appearing on sheets 12 and 11, respectively, are such that there are no totally opaque areas, at least over that part of the framed area through which it is desired to project a defined portion of image "B". Neither of these considerations imposes any objectionable limitations against obtaining a clear-cut, well defined reproduction of image "A" on sheet 11 for presentation when the rays from rear light 19 are interrupted. Therefore, by securing sufficient intensity of illumination from such rear light or lights 19, an adequate intensity of light can be projected through both sheets for causing image "B" to stand out as a clear-cut, well defined picture.

Color effects can easily be added to image "B". For example, if it is desired to have the apartment building of this image stand out in yellow or other colored brick, with the surrounding trees, lawn and shrubbery appearing in green, such is easily accomplished by appropriately tinting sheet 12. This is preferably done on the back side of sheet 12, although it might be done on the front side thereof before the two sheets are joined together, and merely consists in appropriately coloring the areas of sheet 12 corresponding to the building, trees, shrubbery, etc. When image "A" is presented from light rays reflected from the surface of sheet 11 none of these colors will appear, but when light rays are projected through the sign these colors will clearly appear on image "B", thereby heightening the contrast of "before" and "after", where such is desirable.

It will of course be understood that numerous modifications and rearrangements may be adopted without departing from the essence of the invention. For example, while we have de-

scribed the two original negatives 51 and 53 as being made on film, it will of course be understood that these original negatives might be made on photographically sensitized glass plates such as are extensively used in commercial work. The same is also true of the positive reproduction 52 of Figure 4, which might also be made on a glass plate. Therefore, in the accompanying claims wherever general reference is made to one of these elements 51, 52 or 53 as a "sheet" or a "photographic sheet" it will be understood that such contemplates either film or glass plate. In making the composite print 12 it is preferable to use two sheets of film, bearing images "A" and "B", in preference to glass plates, in order to avoid the possible parallax of light rays passing through the greater thickness of the two glass plates, but of course these films might be reproduced from original glass plate negatives. Also, in lieu of print paper as the base medium for the translucent sheets 11 and 12, any other appropriate base medium might be used. For example, a material such as cellophane or like substance might be used as the base material for the sheets 11 and 12, with the surface coated with a light sensitive material. As an alternative, though less desirable method, the composite reproduction represented by the one sheet 12 might in fact consist of two separate sheets, one a reproduction made from sheet 52 and the other a reproduction made from sheet 53. In this instance, however, the light rays would have to pass through three translucent sheets instead of two. In any such three sheet method greater translucency might be obtained by making the "print" of sheet 52 (in which print image "A" will be in negative) and making the "print" of sheet 53 (in which print image "B" will be in positive) on two separate sheets of celluloid film or like material and using these two sheets of film in lieu of the composite print paper sheet 12.

Having thus described our invention, what we claim as new and desire to secure by Letters Patent of the United States is:

1. In a display sign, the combination of a translucent front sheet having image "A" reproduced thereon in positive, a translucent rear sheet having a composite reproduction thereon comprising image "A" in negative and image "B" in positive, and means for projecting light rays through said two sheets, said sheets being arranged whereby the projection of light rays therethrough causes the positive and negative reproductions of image "A" to form counterparts of reversed light transmitting value substantially to obliterate image "A" and to present "B" to view, and whereby the preponderating reflection of light rays from said front sheet presents image "A" to view.

2. In a display sign, the combination of a translucent front sheet having image "A" reproduced thereon in positive, translucent means disposed behind said front sheet having image "A" reproduced thereon in negative and image "B" in positive, and means for projecting light rays through said latter means and through said front sheet whereby during the projection of said light rays the positive and negative counterparts of image "A" substantially obliterate said image and present image "B" to view.

3. In a display sign, a combination of a translucent front sheet having image "A" reproduced thereon in positive, a translucent rear sheet having a composite reproduction thereon comprising image "A" in negative and image "B" in positive, said sheets being arranged with the positive and

- negative counterparts of image "A" in registry, light projecting means disposed behind both sheets for projecting light rays therethrough, and means for causing intermittent projection of such light rays through said sheets, whereby when said rear light rays are interrupted front light rays reflected from said front sheet present image "A" to view and when said rear light rays are projected through said two sheets the positive and negative counterparts of image "A" substantially obliterate said image and present image "B" to view.
4. In a display sign, the combination of a translucent front sheet having image "A" reproduced thereon in positive, rear picture means of translucent material comprising image "A" in negative and image "B" in positive, the negative reproduction of image "A" on said rear picture means being in registry with the positive reproduction of image "A" on said front sheet, means for projecting rear light rays through said rear picture means and said front sheet, and means for causing the intermittent projection of such rays, whereby when said rear rays are interrupted the reflection of front light rays from said front sheet will present image "A" to view and whereby the projection of said rear light rays will substantially obliterate image "A" and present image "B" to view.
- 30 5. In a display sign, the combination of a source of light, a translucent sign disposed in front of said source of light, and means for intermittently interrupting the projection of light rays through said translucent sign, said sign comprising positive and negative reproductions of one image arranged in registry and a positive reproduction of a second image.
6. In a display sign, the combination of a translucent sign, a front source of light for projecting light rays adapted to be reflected from the front of said sign, a rear source of light for projecting light rays through said translucent sign, and means for causing the projection of light rays from said two sources to occur alternately, said translucent sign comprising positive and negative counterparts of one image arranged whereby said positive counterpart is brought to view by said front rays of light and the image is substantially effaced by said rear rays of light, and comprising a positive reproduction of a second image which is brought to view by said rear rays of light.
7. The method of making a display sign of the class described, which comprises producing a photographic negative of image "A", making two positive reproductions of said negative, one of a translucent sheet and the other on a photographic sheet, producing a photographic negative of image "B", printing on a second translucent sheet a composite reproduction of said photographic sheet and said latter negative, and superposing one of said translucent sheets upon the other with the photographic counterparts of image "A" in registry.
- 5 8. The method of making a display sign, which comprises photographically producing positive and negative counterparts of one picture, photographically producing a second picture, and bringing said reproductions together with the positive and negative counterparts of said first picture in registry.
9. In a display sign, the combination of a translucent sign reflecting front light rays striking the front of said sign, a rear source of light for projecting rear light rays through said translucent sign, and means for causing the projection of said rear light rays through said sign to occur intermittently, said translucent sign comprising photographic positive and negative counterparts of one image arranged whereby said positive counterpart is brought to view by said front light rays reflected from said sign and the image is substantially effaced by said rear light rays, and comprising a photographic positive reproduction of a second image which is brought to view by said rear light rays.
10. In a display device, the combination of a source of light, a translucent sign disposed in front of said source of light, and means for intermittently interrupting the projection of light rays through said translucent sign, said sign comprising front and back translucent sheets, a positive reproduction of image "A" on said front sheet, a positive reproduction of image "B" on said rear sheet, and a negative reproduction of image "A" on one of said sheets in registry with said positive reproduction of image "A".
11. In a display device, the combination of a source of light, a translucent sign disposed in front of said source of light, means for intermittently interrupting the projection of light rays through said translucent sign, said sign comprising front and back translucent sheets, said sheets having photographically reproduced thereon the positive and negative counterparts of image "A" and the positive reproduction of image "B" arranged whereby when no light is projected through said sign from said source of light image "A" is brought to view, and when light is projected through said sign from said source of light the positive and negative counterparts of image "A" cooperate substantially to efface said image, and image "B" is brought to view.
12. The method of making a display sign, which comprises photographically producing a positive of image "A" on one sheet, photographically producing a positive of image "B" on another sheet, photographically producing a negative of image "A" on one of said sheets, and superposing one of said sheets upon the other with the photographic counterparts of image "A" in registry.
